CLAIM

The ornamental design for a display screen with graphical user interface for map information, as shown and described.

DESCRIPTION

FIG. 1 is a front view of a first image in a sequence of a display screen with graphical user interface for map information, showing our new design; and,

FIG. 2 is a front view of a second image thereof; The appearance of the image transitions sequentially between the images shown in FIGS. 1 and 2. The process of period in which one image transitions to another forms no part of the claimed design.

The outermost broken lines illustrate a display screen and form no part of the claimed design. The remaining broken

(Continued)

lines, including the hatch patterns, illustrate portions of the graphical user interface that form no part of the claimed design.
